US00D933641S

(12) **United States Design Patent** (10) Patent No.: **US D933,641 S**
(45) Date of Patent: **** Oct. 19, 2021**

(54) **WIRELESS CONNECTIVITY DEVICE**

(71) Applicant: **Amazon Technologies, Inc.**, Seattle, WA (US)
(72) Inventors: **Fred Bould**, Menlo Park, CA (US); **Jeremy Paul Wolf**, San Francisco, CA (US); **Lora Violinova Dimitrova**, San Francisco, CA (US)

(73) Assignee: **Amazon Technologies, Inc.**, Seattle, WA (US)

(**) Term: **15 Years**

(21) Appl. No.: **29/768,313**

(22) Filed: **Jan. 28, 2021**

CLAIM

The ornamental design for a wireless connectivity device, as shown and described.

DESCRIPTION

FIG. 1 is a top, front, right perspective view of a wireless connectivity device;

FIG. 2 is a top, back, left perspective view thereof;

FIG. 3 is a bottom, front, left perspective view thereof;

FIG. 4 is a bottom, back, right perspective view thereof;

FIG. 5 is a front view thereof;

FIG. 6 is a back view thereof;

FIG. 7 is a left-side view thereof;

FIG. 8 is a right-side view thereof;

FIG. 9 is a top view thereof; and,

FIG. 10 is a bottom view thereof.

The dashed broken lines depict portions of the wireless connectivity device that form no part of the claimed design. The dot-dashed broken lines represent boundaries of the claimed wireless connectivity device and form no part of the claimed design.

1 Claim, 10 Drawing Sheets
